UNITED STATES PATENT OFFICE

GEORGE E. WHITLOCK, OF TOLEDO, OHIO, ASSIGNOR TO THE CITY AUTO STAMPING COMPANY, OF TOLEDO, OHIO, A CORPORATION OF OHIO

CUSHION STEP TREAD FOR AUTOMOBILES

Application filed June 3, 1929. Serial No. 367,847.

My invention has for its object to provide a means for securing a cushion sheet material, that may be formed of any suitable composition, to a metal sheet of a supporting body, such as the step of a vehicle or the running board of an automobile. The invention particularly provides a plurality of interlocking devices that are distributed over the area of the tread and which is partially embedded in the composition of which the cushioning material is formed, the protruding portions of the devices being formed in such a manner that they may be readily secured to the supporting sheet material.

The invention may be contained in treads of different forms and, to illustrate a practical application of the invention, I have selected a tread containing the invention as an example of such structures, and shall describe it hereinafter. The tread selected is shown in the accompanying drawing.

Fig. 1 is a perspective view of the running board of an automobile. Fig. 2 is a view of a part of a longitudinal section taken substantially along the plane of the line 2—2 indicated in Fig. 1. Fig. 3 is a view of a transverse section taken along the plane of the line 3—3 indicated in Fig. 2. Fig. 4 is a view of a section of one of the interlocking devices used for securing the cushion tread to the running board.

The running board 1 of the automobile 2 is formed of sheet metal, it being provided with suitable looped central portions 3 that extend lengthwise the running board and form reinforcements for sustaining any ordinary load that may be placed on the surface of the running board. The sheet metal of which the running board is formed is provided with a plurality of holes 4 that are distributed throughout the area of the top of the running board and afford a means for securing the sheet 5 of the cushioning material.

The cushioning material 5 may be formed of any suitable composition commonly used for floor covering. It is provided with a plurality of rivets, such as the eyelets 10, having portions thereof embedded within the sheet 5, portions of the composition 5 entering the central openings 11 of the eyelets to

substantially fill the interior of the eyelets and form thereby a rigid interlock as between the sheet material 5 and the eyelets 10. The protruding parts 12 of the eyelets are inserted in the openings 4 and the ends are flanged over the sheet metal of the running board 1, as at 13, so as to securely fasten the eyelets to the running board and, consequently, to securely fasten the sheet 5 to the top of the running board.

I claim:

1. In a tread for sheet metal supporting members, a cushioning material in sheet form, a plurality of eyelets for securing the sheet material to the sheet metal, the eyelets having flanged portions embedded within the cushioning material and flanged portions extending through the sheet metal and engaging the sheet metal on the side opposite to that on which the sheet material is located, the openings of the eyelets substantially filled with the composition of the sheet material for interlocking the eyelets with the sheet material.

2. In a tread for sheet metal supporting members, a cushioning material in sheet form, a plurality of rivets for securing the sheet material to the sheet metal, the rivets having hollow central chambers in which the cushioning material is located, and having flanged portions embodied within the cushioning material and flanged portions engaging the sheet metal on the side opposite to that on which the sheet material is located.

In witness whereof I have hereunto signed my name to this specification.

GEORGE E. WHITLOCK.
